(57) **CLAIM**

The ornamental design for a wand assembly for use in an architectural-structure covering, as shown and described.

DESCRIPTION

FIG. 1 is a perspective view of a wand assembly showing our new design with features illustrated in broken lines for illustrative purposes and thus not constituting a part of the claimed design;

FIG. 2 is a front elevational view of the wand assembly of FIG. 1;

FIG. 3 is a rear elevational view of the wand assembly of FIG. 1;

FIG. 4 is a left side elevational view of the wand assembly of FIG. 1;

FIG. 5 is a right side elevational view of the wand assembly of FIG. 1;

FIG. 6 is a top plan view of the wand assembly of FIG. 1;

FIG. 7 is a bottom plan view of the wand assembly of FIG. 1;

FIG. 8 is a perspective view of an alternate embodiment of a wand assembly showing our new design with features illustrated in broken lines for illustrative purposes and thus not constituting a part of the claimed design;

FIG. 9 is a front elevational view of the wand assembly of FIG. 8;

FIG. 10 is a rear elevational view of the wand assembly of FIG. 8;

(Continued)

FIG. 11 is a left side elevational view of the wand assembly of FIG. 8;

FIG. 12 is a right side elevational view of the wand assembly of FIG. 8;

FIG. 13 is a top plan view of the wand assembly of FIG. 8; and,

FIG. 14 is a bottom plan view of the wand assembly of FIG. 8.

The broken lines in the drawings are environmental and for illustrative purposes only depicting portions of the wand assembly that form no part of the claimed design.

The unshaded surfaces shown between the solid lines and the broken lines form no part of the claimed design.
